UNITED STATES PATENT OFFICE.

HERBERT A. BROCKWAY, OF DENVER, COLORADO.

PNEUMATIC TOOL.

No. 893,138.

Specification of Letters Patent.

Patented July 14, 1908.

Application filed March 18, 1907. Serial No. 368,084.

To all whom it may concern:

Be it known that I, HERBERT A. BROCKWAY, a citizen of the United States of America, residing at Denver, in the county of Denver and State of Colorado, have invented certain new and useful Improvements in Pneumatic Tools, of which the following is a specification.

My invention relates to improvements in the class of pneumatically operated devices in which a reciprocating hammer is arranged to impinge upon a drill bit or other tool for the purpose of drilling holes in rock or other substances, to chip, calk or rivet and in short 15 to be of service in all operations requiring a succession of concussive blows.

The main object of the invention is to provide a valveless pneumatic tool in which the air employed to actuate the hammer or piston 20 is distributed in a manner to insure the derivation of the maximum of efficiency from the minimum of motive power, by varying the pressure of motive fluid which may be opposed to the effective stroke of the piston, 25 so as to render it greatest when the most pressure is needed and least at the time the least pressure is required.

Further objects of my invention will be brought out in the following description, 30 reference being had to the accompanying drawings in the various views of which like parts are similarly designated and in which

Figure 1—represents a vertical, longitudinal section through the device, Fig. 2, an enlarged transverse section taken along a line 2—2, Fig. 1, Figs. 3, 4 and 5—enlarged fragmentary, vertical, longitudinal sections of the cylinder, hammer and adjacent parts, illustrating the positions successively assumed by the hammer during the operation 40 of the device, Fig. 6—an enlarged transverse section taken along a line 6—6, Fig. 3, Fig. 7—an enlarged transverse section taken along a line 7—7, Fig. 3, Fig. 8—an enlarged 45 cross section taken along a line 8—8, Fig. 1, Fig. 9—an enlarged cross section along a line 9—9, Fig. 3.

Referring to the drawings, the reference numeral 2 designates the cylinder, 3 the 50 hammer or piston having a longitudinal reciprocating movement therein, 4 the striking block upon which the hammer or piston impinges during each forward movement, and 5 the chuck designed to hold the multilateral 55 drill bit 6.

The cylindrical, longitudinal bore of the

barrel 2 which, in practice, contains the piston 3, includes four sections or chambers different in diameter, the largest one, 7, of which is situated at the extreme, rear end of 60 the cylinder and being designed to receive the air during the return stroke of the piston, may be called the compression and expansion chamber. The adjoining, reduced section 8 contains and guides the piston head as 65 will hereinafter be described, while the following, further reduced section 9 is provided with an annular channel 10 which connects by means of an opening 10^a in the cylinder wall, with an admission pipe 11. A small 70 port 12 furthermore connects the said opening with the preceding chamber 8.

The portion of the cylinder adjoining the chamber 9, is counterbored to produce the enlarged exhaust chamber 13 which communicates with the atmosphere by a plurality of radially extending exhaust openings 14 in the cylinder wall. The foremost portion of the cylinder, adjoining the last named chamber is bored to accommodate the striking 80 block 4 and the chuck 5, as will hereinafter be described.

The piston 2, turned to fit the admission chamber 9 of the cylinder, has an enlarged head 15, the diameter of which equals that of 85 the chamber 8 and which is provided intermediate its extremities, with a peripheral, annular recess 16. A central, longitudinal bore 17, extends from its rearmost surface forwardly to terminate in a plurality of inclined air conduits 18 which open in the peripheral surface of the foremost portion of the piston in advance of and in proximity to the recess 16. The piston 3 is furthermore provided with a longitudinally extending air 90 passage 19, the extremities of which communicate respectively, with a lateral opening 20 located in its periphery in proximity to the head 15 and with a similar port 21 adjacent to its opposite, foremost end. A 100 third port 22 extends from the peripheral surface of the foremost portion of the piston into the passage 19, intermediate its extremities.

The proportionate length of the various 105 chambers in the cylinder and parts of the piston as well as the relative location of the several air-ports will be made apparent during the description of the operation of the device, forming part of this specification.

The cylinder 2 is provided at its rearmost extremity with a socketed head or cap 23

having an internal coarse, screw thread shaped in the form of a ratchet tooth, which operatively engages a corresponding, peripheral thread upon the cylinder. A bolt 24 extending through a correspondingly formed opening 25 in a tangential enlargement of the head, projects into a peripheral recess 26 in the cylinder in engagement with a shoulder 27. This arrangement is designed to maintain the two parts in their relative positions, while the shape of the recess, as shown in Fig. 10 of the drawings, is such as to permit adjustment of the head in case of wear.

The head or cap 23 is provided with a socketed, cylindrical, concentric extension 28 and the wall or partition 29 dividing the two sockets has an angular air passage 30 which connects the socket 28^a with a smaller, internally threaded socket 31 in the peripheral surface of the head, into which projects a co-operatively threaded nipple on a three way valve 32 by which the air employed to operate the device, is admitted. The socket 28^a is internally threaded to receive and hold a corresponding part of a handle 33. The handle 33, shown in Fig. 1 of the drawings, consists of a yoke 35 terminating in a cylindrical, hollow sleeve 36, which in practice, surrounds the socketed extension 28 of the cylinder head. A plunger 42 which is fitted into a bore 39 of a plug 38 in the socket 28^a, is rotatably connected with the yoke 35, and the air admitted through the passage 30, into the socket 28^a, forms an absorptive cushion which by action upon the movable plunger and the therewith connected handle prevents communication to the latter of the jars to which the cylinder is subjected during the operation of the machine.

40 A handle 53 screwed into an opening 54 in the cylinder opposite to the before mentioned socket 31, affords further means to hold and steady the drill during its operation.

The front portion of the cylinder occupied by the striking block 4 has an internal, annular ridge 55 bored to admit the reduced portion 4^a of the cylindrical block, the extremity of which projects normally into the exhaust chamber 13. The shoulder 56 produced by the ridge 55 is normally in contact with the shoulder 57 of the larger portion of the block, and a plurality of radially air passages 58 extend at this point through the cylinder wall to communicate with an equal number of openings 59 which diverge from a central opening 60 in the front end of the block. This opening 60 communicates with a longitudinal bore 61 in the drill bit through which, in practice, air is conducted to the breast of the drill hole into which the latter projects, as will hereinafter be described.

The chuck 5 is provided with a peripheral screw thread and secured in the correspondingly threaded mouth of the cylinder in a manner similar to that described for securing

the cap 23, a transverse bolt 61 being employed to maintain it in position.

A sleeve 62 provided with an internal, annular recess 63 surrounds that portion of the cylinder which contains the air passages 58 and may be held in either one of two positions by means of a spring-actuated dog 64 which being disposed in a socket in the peripheral surface of the cylinder, extends in one of two internal grooves 65 in the sleeve. 75

The recess 63 in the sleeve is connected with the before mentioned air inlet pipe 11, by means of a flexible conduit 66, the flow through which is controlled by a valve or cock 67. When the sleeve is in its rearmost position as shown in Fig. 4 of the drawings, its recess 63 communicates with the exhaust ports 14 leading to the exhaust chamber 13, as well as with the air passages 58 which register with those in the striking block and the air exhausted during each stroke of the reciprocating piston, is thus conducted into the longitudinal bore of the drill bit 6. When the sleeve is in its other, forward, position, illustrated in Fig. 5, its recessed portion extends only over the radial passages 58 and the air exhausted through the ports 14 is free to pass into the atmosphere. 80

By opening the valve 67 the recess is brought in communication with the inlet pipe 11, in consequence of which live air is constantly fed into the longitudinal bore 61 in the drill bit 6. The air thus being introduced into the bore in the rock into which the bit projects, forcibly strikes the breast of the hole and reverberating, carries the chips and dust caused by the action of the drill upon the rock, out of the mouth of the opening and into a receptacle 68 placed around the drill bit and held in engagement with the surface of the penetrated wall by means of a coiled spring 69 likewise surrounding the drill bit and engaging the outer end of the chuck 5 and the opposite portion of the receptacle. 100

The dust receptacle has been made subject of a separate application for patent, Serial #376,012, filed May 27—1907.

Having thus described the mechanical construction of my invention its operation and the advantages derived thereby will now be described.

When the differential area piston is in the rearmost position, as illustrated in Fig. 4, the ports 18 which communicate with the central core 17, register with the annular channel 10 and the compressed air or other motive fluid introduced into the said channel through the duct 11, is free to pass into the compression chamber 7 of the cylinder. The piston being situated in the chamber 8 of the cylinder which in diameter corresponds with the head 15, projects with its foremost portion into the adjoining section 9, the diameter of which equals that of the 120 125 130

main body of the piston and the annular space between the peripheral surface of the said body and the encircling wall of the chamber 8, being in direct communication 5 with the pressure supply by means of the small auxiliary port 12, is filled with live air which exerting a pressure upon the shoulder 74 which constitutes the smaller area of the head 15, tends to move the piston in a rearward direction. As the area of the face of the piston within the chamber 7, greatly exceeds that of the shoulder 74, the hammer impelled by the expansion of the fluid in the compression chamber, is moved forwardly to 10 impinge upon the striking block 4, which communicates the blow to the juxtaposed tool 6.

An elastic washer 75 placed between the striking block and the opposite surface of the chuck 5, limits and mitigates the concussive action of the said block upon the chuck and aids in returning the former to its normal position.

Should, by reason of wear or omission of 25 the washer, the block 4 remain in the advanced position so that its rear surface extends in a plane with or beyond the rear edge of the annular ridge 55 and the end of the piston is, in consequence, projected 30 through the exhaust chamber into the portion of the cylinder bore occupied by the chuck, the fact that the said portion corresponds in diameter with the piston, will cause the formation of an air cushion to prevent 35 the piston from coming in contact with the aforesaid shoulder of the ridge 55.

The smaller area of the differential piston is during its forward movement, exposed to the pressure of the air introduced into the 40 chambers 8 and 9 through the duct 12 and the channel 10 until it reaches the position illustrated in Fig. 5, when the rear edge of the circumferential recess, passing the shoulder between the said chambers, cuts off the 45 supply from the channel 10. The port 21 of the conduit 19 has simultaneously opened into the exhaust chamber 13, causing a partial exhaust of the air which, surrounding the piston, pressed upon the shoulder 74 of the 50 head, and during further forward movement, the amount of air exhausted will be increased as the intermediate port 22 advances beyond the point 76 into the chamber 13. The result is that the back pressure, exerted 55 upon the smaller area of the head, is gradually reduced as the piston advances and the efficiency of the expanding air in the chamber 7 is proportionately increased.

When the piston reaches its foremost position, the greater part of the air contained in the expansion chamber 7, is exhausted through the ports 18 which now open into the exhaust chamber and as the air supply has continuously remained in communication 60 with the space between the piston body

and the wall of the piston chamber 8, the pressure upon the shoulder 74 of the head exceeding that of its rear face will impel the piston in rearward direction.

During the return stroke of the piston the 70 ports 21 and 22 of the channel 19 perform a function opposite to that accomplished during the forward movement or with other words, when the ports 22 and 21 pass successively beyond the shoulder 76 between 75 the chambers 13 and 9, the exhaust of the air surrounding the piston will be gradually decreased and the pressure upon the shoulder 74 of the head be proportionately increased, which pressure is further augmented 80 through instrumentality of the annular recess 16 in the piston, the rear end of which extends beyond the shoulder 77 between the chambers 9 and 8, when the front end of the piston passes out of the exhaust chamber 85 and by connecting the air space around the cylinder with the channel 10, causes the full pressure to be exerted upon the shoulder 74.

It will thus be observed that by my improved construction the speed and efficiency 90 of the hammer are increased as it advances towards the striking block to be greatest when the blow which actuates the tool, is delivered and that during the return stroke the pressure upon the hammer head increases in proportion to the distance traveled and the constantly increasing degree of compression of the remaining air in the expansion chamber 7. It will be understood 95 that the number of intermediate ports between the terminal ports 20 and 21 of the passage 19 in the piston, may be increased to further graduate the exhaust from the space between the piston and the wall of chamber 8, and that to insure effective operation of 100 the improved device, the combined areas of the orifices of the exhaust ports leading from the said passage, should at no time exceed the area of the auxiliary inlet port 12. It should furthermore be observed that the 105 seeming disadvantage of a minimum of pressure at the beginning of the return stroke, is fully offset by the action of the rebounding striking block upon the piston.

Having thus described my invention what 115 I claim is:—

1. In a valveless pneumatic tool, a cylinder, a piston fitted for reciprocation therein, the said cylinder and piston having cooperative means for continuously directing fluid 120 pressure against a face of the piston, in opposition to its forward movement, and means to cause variation of the said pressure so as to render it greatest at the beginning and least at the termination of the said movement. 125

2. In a valveless pneumatic tool, a cylinder having pressure supply and exhaust ducts, a piston fitted for reciprocation therein, the said cylinder and piston having cooperative means for continuously directing 130

motive fluid from the supply port against a face of the piston, in opposition to its forward movement and means to direct part of the said fluid to the exhaust port during the 5 latter part of the said movement.

3. In a pneumatic tool, a cylinder having pressure supply and exhaust ducts, a differential piston fitted for reciprocation therein, means to maintain continuous communication 10 between the supply duct and a face of the said piston and means to cause reduction of the pressure upon the said face during the latter part of the forward stroke of the piston.

4. In a pneumatic tool, a cylinder having 15 pressure supply and exhaust ducts, a differential piston fitted therein for reciprocation by pressure of the motive fluid upon its working faces, and means to cause discharge of motive fluid from the said faces during 20 the latter part of the forward stroke of the piston.

5. In a pneumatic tool, a barrel bored to form successively arranged piston, admission and exhaust chambers of different diameters, 25 and having a pressure supply duct opening in the admission chamber and an auxiliary, smaller pressure supply duct communicating with the piston chamber, a reciprocating differential piston having an enlarged head 30 fitted in the piston chamber and a smaller body portion fitted in the admission chamber, the said body being formed with interconnected, peripheral ports located so that one will continuously open into the piston 35 chamber during the movement of the hammer, while the other opens into the exhaust chamber during the second half of the forward stroke. 40

6. In a pneumatic tool, a barrel bored to form successively arranged piston, admission and exhaust chambers of different diameters, and having a pressure supply duct opening 45 in the admission chamber and an auxiliary, smaller pressure supply duct communicating with the piston chamber, a reciprocating, differential piston having an enlarged head fitted in the piston chamber and a smaller body portion fitted in the admission chamber, the said body being formed with an internal 50 passage, a port leading therefrom to the periphery of the hammer in proximity to its head and a series of successively arranged, similar ports at its foremost end, the said ports being located so that the said series will open in the exhaust chamber when the piston has reached its foremost position. 55

7. In a pneumatic tool, a barrel bored to form successively arranged piston, admission and exhaust chambers of different diameters 60 and having a pressure supply duct opening in the admission chamber and an auxiliary, smaller pressure supply duct communicating with the piston chamber, a reciprocating, differential piston having an enlarged head 65 fitted in the piston chamber and a smaller

body portion fitted in the admission chamber, the said body being formed with an internal passage, a port leading therefrom to the periphery of the piston in proximity to its head and a series of successively arranged, 70 similar ports at its foremost end, the ports comprised in the said series being located so they will open in the exhaust chamber when the piston has reached its foremost position, while the combined areas of their orifices is 75 less than the area of the auxiliary supply duct.

8. In a pneumatic tool, a barrel bored to form successively arranged piston, admission and exhaust chambers of different diameters 80 and having a pressure supply duct opening in the admission chamber and an auxiliary, smaller pressure supply duct communicating with the piston chamber, a reciprocating, differential piston having an enlarged head 85 fitted in the piston chamber and a smaller body portion fitted in the admission chamber, the said body being formed with interconnected, peripheral ports located so that one will continuously open into the piston 90 chamber during the movement of the hammer, while the other opens into the exhaust chamber during the second half of the forward stroke, and with a circumferential recess so located that during the forward stroke 95 of the piston it will establish communication between the piston and admission chambers until the port adjacent the foremost end of the piston has opened into the exhaust chamber. 100

9. In a pneumatic tool, a cylinder having a main supply duct and a smaller auxiliary duct leading therefrom, and a differential area piston fitted for reciprocation therein, and having a circumferential recess so located as to establish communication between both supply ducts and its smaller area during the first part of its effective stroke and between the said area and the auxiliary port only, during the latter part of the said stroke. 105

10. In a pneumatic tool, in combination a cylinder formed with successively arranged piston, admission and exhaust chambers of different diameters, a bore at its front end to receive a striking block and a recess intermediate the said bore and the exhaust chamber, and of a diameter equal to that of the admission chamber, a striking block within the bore, normally projecting into the recess, a differential piston having an 110 enlarged head fitted in the piston chamber and a smaller body portion fitted in the admission chamber and having interconnected, peripheral ports so located that one opens continuously into the piston chamber, while the foremost one is closed by engagement with the wall of the recess during excessive forward movement of the former. 115

11. In a pneumatic tool, a cylinder having main supply and exhaust ducts and a smaller 120

auxiliary duct leading from the former, and a differential area piston fitted for reciprocation therein, the said cylinder and piston having coöperative means to establish, during its movement, intermittent communication between the smaller area of the piston head and the main supply duct and continuous communication between the said area and the auxiliary duct, and the said piston having means which, in coöperation with the said exhaust ducts, will cause discharge of part of the motive fluid pressing upon the said area, during the latter part of its movement in one direction.

15. 12. In a pneumatic tool, a barrel bored to form successively arranged piston, admission and exhaust chambers of different diameters and having a pressure supply duct opening in the admission chamber and an auxiliary, smaller pressure supply duct communicating with the piston chamber, a reciprocating, differential piston having an enlarged head fitted in the piston chamber and a smaller body portion fitted in the admission chamber, the said piston being adapted to maintain communication of both the supply ducts with the smaller area of its head during the first part of its forward stroke and of the auxiliary one only during the completion of the stroke.

13. In a pneumatic tool, the combination of a cylinder bored to form successively arranged piston, admission and exhaust chambers of different diameters and having an annular channel in the admission chamber, a supply duct opening in the said channel and an auxiliary duct opening into the piston chamber, a differential piston having an enlarged head fitted in the piston chamber and a smaller body portion fitted in the admission chamber and having peripheral ports in communication with the larger area of its head and normally registering with the said channel.

45. 14. In a pneumatic tool, a body member having a threaded extremity, a coöperatively threaded member in engagement therewith, the exterior member having an opening axially in tangential relation to its threaded surface and the interior member having a shoulder formed by a depression in its periphery, and a locking member, longi-

tudinally movable in the said opening and adapted to engage the said shoulder when the parts are in their relative positions. 55

15. In a pneumatic tool a barrel bored to form successively arranged piston, admission and exhaust chambers of different diameters and provided with a series of pressure supply ducts, a reciprocating differential piston having an enlarged head fitted in the piston chamber and a smaller body portion fitted in the admission chamber, the said piston having means to establish simultaneous communication of the said pressure supply ducts with the smaller area of its head while in the first part of its forward and in the last part of its return stroke, and continuous communication of one of the said supply ducts with the smaller area. 60

16. In a pneumatic tool a barrel bored to form successively arranged piston, admission and exhaust chambers of different diameters, and having principal and auxiliary pressure supply ducts, a reciprocating differential piston having an enlarged head fitted in the piston chamber and a smaller body portion fitted in the admission chamber, the said piston having means to establish communication of the auxiliary supply duct with the smaller area of its head during the last part of its forward and the first part of its return stroke. 75

17. In a pneumatic tool, a barrel formed with chambers common thereto, and having principal and auxiliary pressure supply ducts, a reciprocating differential area piston fitted in said barrel and having means to establish in coöperation with relative means on the cylinder, communication of the auxiliary pressure supply duct with the smaller area of its head during its entire forward stroke, and to exhaust part of the motive fluid exerting pressure upon the said area, during the last part of its forward and the first part of its return stroke. 80

In testimony whereof I have affixed my signature in presence of two witnesses.
